UNITED STATES PATENT OFFICE.

WILLIS S. RICHARDSON, OF NEWARK, NEW JERSEY.

WATCHMAKER'S TOOL.

No. 832,810.

Specification of Letters Patent.

Patented Oct. 9, 1906.

Application filed November 15, 1905. Serial No. 287,444.

To all whom it may concern:

Be it known that I, WILLIS S. RICHARDSON, a citizen of the United States, and a resident of Newark, in the county of Essex 5 and State of New Jersey, have made and invented certain new and useful Improvements in Watchmakers' Tools, of which the following is a specification.

My invention relates to an improvement 10 in watchmakers' tools.

In stores, shops, and other places wherein a number of watches are kept or retained for regulation much time and labor are consumed in daily winding the watches by hand.

15 The object of my invention is to provide a device whereby this winding may be effected with a material saving in time and labor, and, further, to so construct and arrange the several parts as to adapt it to the winding of 20 watches having crowns of different sizes.

With these and other ends in view the invention consists in certain novel features of construction and combinations of parts, as will be hereinafter fully described, and pointed out in the claims.

25 In the accompanying drawings, Figure 1 is a top plan view of my improved device. Fig. 2 is a view in side elevation thereof. Fig. 3 is a front view of the spring-actuated winding-arms. Fig. 4 is a sectional view of a part of the device.

Referring to the drawings, A represents the base-plate, adapted to be secured to a bench or other support, and, as clearly illustrated in Fig. 2, may be provided with the downwardly-extending lug B, whereby the tool may be clamped in a vise or other place for the purpose of securely holding the same while in use.

30 Extending upwardly from the base A are the plates or standards C, having journaled in the upper ends thereof the shaft D, adapted to rotate therein, but prevented from endwise movement by means of the collar E, 35 pinned or otherwise secured to the shaft. To one end of this shaft is secured the handle F for the purpose of rotating the same, the opposite end G of said shaft being threaded. To the extreme end of the shaft is fastened 40 the plate H, provided with the extensions h, preferably three in number, each of said extensions being slotted and having pivoted therein the winding-arms I, the outer ends of which are adapted to engage with the grooved 45 or corrugated crown K of a watch, the engaging edges of said arms being beveled,

as shown at k, to allow them to enter the grooves or corrugations in said crown. These three winding-arms I are connected by a spring L, the tendency of which is to 60 open or spread apart the engaging ends of said arms and to close or spring together the rear ends of the same, which rear ends bear upon the nut M, threaded on the end G of said shaft D and preferably made in the 65 form of a truncated cone, having the milled edge N at the base thereof.

By turning the regulating-nut M in one direction—that is, toward the extreme end of the shaft—the ends of the arms bearing thereon will be spread apart, closing or bringing together the opposite or engaging ends of said arms, and when the nut is turned and travels in the opposite direction upon the shaft the spring L will operate to open 70 or spread apart the engaging ends of said arms, at the same time retaining the opposite ends thereof in engagement upon the cone-shaped nut M.

In practice the tool is fastened or secured 80 in a vise or other proper support. The crown of the watch is then placed between the engaging ends of the arms I and the nut M turned until the beveled edges k of said arms engage with the grooved or corrugated crown 85 K. By turning the handle F and rotating the shaft D the crown K is turned, the watch of course being held stationary in the operator's hand, until the winding of the watch is completed. This operation can be effected 90 with much less labor and in much quicker time than is now consumed in winding the watches in the ordinary way by hand.

Having fully described my invention, what I claim as new, and desire to secure by Letters Patent, is—

1. A watch-winding tool having in combination a support, a shaft rotatable therein, having one end threaded and the opposite end provided with means whereby it may be 100 rotated, a plate fastened to the extremity of the shaft and provided with radial extensions said extensions having inwardly-extending slots, winding-arms pivotally mounted between their ends in said slots, a unitary 105 expanding member engaging with each of the arms and expanding their operating ends in unison, and a follower on the threaded portion of the shaft adapted to operate the inner ends of the arms to cause the outer 110 ends of said arms to engage the crown of a watch.

2. A watch-winding tool having in combination a support, a shaft rotatable therein, having one end threaded and the opposite end provided with means whereby it may be rotated, a plate fastened to the extremity of the shaft and provided with radial extensions said extensions having inwardly-extending slots, winding-arms pivotally mounted between their ends in said slots, a single spring substantially concentric with the shaft and passing through each of said arms.

to expand them in unison, and means for rocking the arms about their pivots to cause the outer ends of the arms to grip the crown of a watch.

Signed at Newark, in the county of Essex and State of New Jersey, this 14th day of November, A. D. 1905.

WILLIS S. RICHARDSON.
